UNITED STATES PATENT OFFICE

1,959,707

FEEDING MECHANISM FOR SEWING MACHINES

Grover C. Cooper and Joseph Mann, Philadelphia,
Pa., assignors to Union Special Machine Company,
Chicago, Ill., a corporation of Illinois

Application July 9, 1931, Serial No. 549,781

7 Claims. (Cl. 112—214)

The invention relates to a feeding mechanism for sewing machines, and more particularly to a feeding mechanism having an upper positively rotated feed roller and a lower freely rotated feed roller cooperating therewith.

An object of the invention is to provide a feeding mechanism of the above type wherein the upper feed roller is actuated from a shaft above the work support which is intermittently operated and which is connected to the feed roller by a flexible connection which permits the feed roller to freely move up and down.

A further object of the invention is to provide a machine of the above type wherein the feed roller is located directly in rear of the needle and operates upon the material for feeding the same after the sections thereof are stitched together, and wherein a presser foot lightly bearing on the material in the region of stitching, holds the material in contact with the work support during the entire stitch cycle.

A still further object of the invention is to provide a feeding mechanism of the above type wherein the actuating shaft is intermittently operated and prevented from retrograde movement by coiled spring clutch members.

These and other objects will in part be obvious and will in part be hereinafter more fully disclosed.

In the drawings which show by way of illustration one embodiment of the invention—

Figure 1 is a front view of a machine embodying the improvements;

Fig. 2 is an end view hereof, partly in section and showing the feed roller operating connection;

Fig. 3 is a view from the rear of the machine with certain parts sectioned;

Fig. 4 is a vertical sectional view transversely of the line of feed, and showing the mounting for the feed rollers;

Fig. 5 is a view partly in plan and partly in section showing the relation of the feed roller to the stitching mechanism;

Fig. 6 is a view partly in side elevation and partly in section showing the intermittent operating mechanism for the actuating shaft;

Fig. 7 is a sectional view on the line 7—7 of Fig. 6, showing the clutching member;

Fig. 8 is a section on the line 8—8 of Fig. 7;

Fig. 9 is a section on the line 9—9 of Fig. 7, and

Fig. 10 is a diagrammatic view showing the arrangement of the fabric sections to the feed

rollers in the joining of a waist band to a body fabric.

The invention is directed broadly to a feeding mechanism for a sewing machine which includes an upper intermittently rotated feed roller 60 located directly in rear of the needle, and a lower freely rotating feed roller cooperating therewith. The upper feed roller is mounted on a supporting presser bar which is yielding urged toward the work support. A presser foot 65 lightly bears on the material in front of the feed rollers and holds the material pressed against the work support during the entire stitch cycle. The feed roller is actuated by an operating shaft mounted in fixed bearings above the work support, and connected to the feed roller by a flexible connection which permits the feed roller to freely move up and down. The operating shaft is intermittently actuated by a clutch mechanism which includes two coiled spring 70 clutch members, one of which positively imparts a step by step turning motion to said shaft, while the other prevents retrograde motion in the shaft. This clutch mechanism is operated from the main shaft and imparts through the 75 feed roller, feeding movements to the fabric sections.

The invention will be better understood by a detail description of the present illustrated embodiment of the invention. The machine includes a work support 1 to which is attached a throat plate 2. Mounted on an overhanging arm 3 is a needle head 4. The present machine is constructed for reciprocating the needle and for vibrating the same laterally so as to make 90 zigzag stitches. The needle indicated at 5 is carried by a needle bar 6 which is mounted for reciprocation in a gate 7. The needle bar is reciprocated by a needle lever 8, and the gate is oscillated by a rock shaft 9. This rock shaft 95 is in turn oscillated by a vibrating segment 10 cooperating with an eccentric on a stub shaft which is turned by a gear 11. The gear 11 meshes with a gear 12 on the main actuating shaft 13.

Cooperating with the needle beneath the work support is a looper 14 which is oscillated and given a needle avoiding movement, and which cooperates with the needle at each stitch formation. The parts above described are of the 105 ordinary construction, and further detail description of the stitching mechanism is not thought necessary. It will be understood that from certain aspects of the invention, the needle bar may be reciprocated in a fixed line, and a 110

- straight line of stitching produced instead of a zigzag line of stitching. It will be understood that more than one needle may be used so that a plurality of lines of stitching may be produced.
- 5 The invention has to do particularly with a feeding mechanism and its disposition relative to the needle. The material is held on the work support by a presser foot 15. Located beneath the work support is a freely rotating feed roller 16. Said feed roller is carried by a shaft 17 which is mounted for free rotation in a bracket 18 attached to the under side of the work support. The work support is provided with an opening 19 and the feed roller 16 projects through said opening so as to support the material. Cooperating with this feed roller 16 is an upper feed roller 20. The upper feed roller 20 is intermittently rotated. Both of the feed rollers are provided with serrated faces which engage the fabric. The feed roller 20 is formed as a part of a sleeve 21. The roller is mounted for rotation on a bearing 22. This bearing 22 is fixed to the lower end of the presser bar 23 which is mounted in suitable bearings in the head at the end of the overhanging arm. A leaf spring 24 bears on a lug 25 attached to the presser bar and normally tends to force the presser bar yieldingly in a downward direction holding the upper feed roller in contact with the material and gripping the material between the feed rollers. The presser bar may be raised by a lever 26 in the usual manner. It will be noted that the feed rollers 16 and 20 are positioned in rear of the needle, and they, therefore, operate on the fabric sections after they are stitched together.
- The machine is particularly adapted for the stitching of waist bands of body fabrics. In Fig. 10 of the drawings, there is shown diagrammatically a waist band being attached to a body fabric. The body fabric is indicated at B. The waist band consists of a pants curtain or facing strip F and a stiffening buckram strip C. The pants curtain and stiffening strip are shown as stitched together by a line of stitching s. This, however, is not essential. The pants curtain has the edge portion thereof infolded as indicated at f. As indicated in this figure, the needle passes through the fabric sections at the line a, a, on one reciprocation, and through the fabric at the line b, b, on the next reciprocation. This lays the needle thread across the folded edge of the pants curtain and produces a stitching which resembles whip stitching. The needle passes through the body fabric and the stiffening strip at both reciprocations. The feed rollers indicated diagrammatically at 16 and 20 in this figure, are so disposed as to engage the fabric sections and firmly grip and feed the same. The upper feed roller is the one that is positively rotated, and this feed roller engages the pants curtain which is cut on the bias in order to have the proper shaping when used for a waist band for trousers, and which is always a very thin material. The feed roller not only engages directly the pants curtain, but it engages the material after the parts are stitched together. There is no other feed in the machine than the two feed rollers. This insures the feeding of the pants curtain as well as the heavy body fabric and buckram strip smoothly without wrinkling or in any way drawing the materials. The presser foot 15 is pivoted to an arm 27 which in turn is pivoted at 28 to a bracket 29. The bracket 29 is fixed to the head of the ma-
- chine by a screw 30. A spring 31 is coiled about a screw stud 32 threaded into the bracket and is anchored to the bracket. This spring 31 rests in a guide channel in the screw stud 33 and has the end thereof bent laterally at 34 so as to bear on the presser foot. This spring is very light and is the only means for yieldingly pressing the foot against the material, and therefore, the material is not clamped firmly against the work support, but is rather held lightly by this presser foot which serves to strip the fabric from the needle on the upstroke of the needle. It is noted that the presser foot is not carried by the presser bar, as is usual in a sewing machine. The upper feed roller only is carried by the presser bar and serves the combined function of firmly gripping the fabric and pressing the same against the lower feed roller and of imparting feeding movements to the fabric when the upper feed roller is rotated.
- The feed roller 20 has intermittent rotations imparted thereto by means of a flexible shaft 35 which is attached to an actuating shaft 36 mounted in a bracket 37 attached to the upper face of the work support 1.
- The flexible connection between the actuating shaft and the upper feed roller consists of a member 38 which is fixed to the sleeve carrying the upper feed roller, a sleeve 39 which is fixed to the actuating shaft, and an intermediate member which includes a central sleeve 40, a forked member 40^a secured thereto by a suitable set screw, and a forked member 40^b having a sliding telescoping engagement with the sleeve. The member 40^a is connected to the member 39 by the usual universal joint connection. The member 40^b is also connected to the member 38 by the usual universal joint connection. This intermediate member transmits the movements of the actuating shaft to the feed roller, and at the same time, permits the feed roller to freely move up and down due to cross seams or increased thickness in fabric sections.
- The actuating shaft receives its movements from the main actuating shaft 13 through a train of devices which include an adjustable crank 42 on the end of the main actuating shaft, a rocker 43 which is oscillated from this crank, and a clutch mechanism to be described. The crank 42 is connected by a link to an arm 45 which is fixed to the rocker 43. The rocker 43 is fixed to a shaft 46 journaled in bearings in the bed of the machine, and fixed to this shaft 46 is the upstanding arm 47. A link 48 is pivotally connected to the upper end of the arm 47 and its connection to the arm may be shifted. This link 48 at its other end is pivoted at 49 to an arm 50 attached to a collar 51 which is freely mounted on the actuating shaft 36. Mounted on the shaft 36 is a sleeve 52 which is secured to the shaft by a set screw 53. This sleeve has reduced portions at each side of a central collar portion. A spring 54 is tightly wound around the sleeve 52 at one side of the central collar portion, and one end of this spring is secured to the collar 51. The other end of the spring is free, but is tending at all times to frictionally grip the sleeve 52. Also mounted on the sleeve 52 is a spring 55 which is wound in the opposite direction and which is free at its inner end to be wound so as to tightly grip the sleeve. This spring 55 at one end is attached to a collar 56. The collar 56 is freely mounted on the shaft 36 and is secured to a bolt 57 which prevents the collar 56 from turning. When the arm 50 is 150

turned in a clockwise direction, as viewed in Figures 6 and 8, it will tend to wind the spring 54 tighter, and cause said spring to grip the sleeve 52 and turn the sleeve and shaft 36. At this time, the spring 55 is loosened so as to release its grip on the collar 52 and thus the shaft 36 is free to turn. When the arm 50 is turned in a counter clockwise direction, this tends to unwind the spring 54, thus releasing its grip on the collar 52 so that the spring may be moved to a new gripping position, and at this time, the spring 55 grips the sleeve 52 and prevents counter clockwise motion in said sleeve. Thus it is apparent that the spring 54 becomes the operating clutch for intermittently rotating the shaft 36, while the spring 55 becomes the clutch for intermittently gripping the shaft and preventing retrograde movement thereof when the spring 54 is returning for its new gripping connection. From the above it will be noted that when the arm 50 is turned to give a feeding motion to the shaft, said shaft will be at once gripped and turned; and likewise when the arm is moved in the opposite direction to position the same for its next feeding movement the spring will at once grip the shaft and prevent any retrograde movement. It is this immediate gripping of the shaft by the springs that takes out all lost motion and insures a uniform feed length. When the fabric is carried forward by the turning of the feed roller and the feed roller stops, it will hold the fabric positively in its new set position for the needle to enter.

The operation of the feeding mechanism is thought to be clear from the detail description which has been given above. At each stitch cycle, the rocker is oscillated and imparts through the spring clutch a set rotation to the actuating shaft which in turn imparts a set rotation to the upper feed roller. This movement of the upper feed roller is timed so as to take place when the needle is above the material, and preferably on its downward movement, so that the stitches have been formed and set, joining the fabric sections, and the joined fabric sections are pulled upon by the gripping feed rollers and fed so as to position the same for the next needle penetration.

It is obvious that modifications may be made in the details of the mechanism shown and described without departing from the spirit of the invention as set forth in the appended claims.

Having thus described the invention, what we claim as new and desire to secure by Letters Patent, is—

1. In a sewing machine, a work support, stitch forming mechanism including a needle, a feeding mechanism including a feed roller located above the work support and in rear of the needle, means for supporting said feed roller for vertical movement while maintaining the axis thereof horizontal, a freely rotating feed roller mounted beneath the work support and projecting through the opening therein and cooperating with said feed roller above the work support, a shaft mounted in fixed bearings above the work support, a flexible connection between said shaft and said feed roller above the work support, a collar mounted on said shaft for free movement thereon, means for oscillating said collar, a spring connected to the collar and wound tightly about said shaft, so as to grip the shaft for turning the same when the collar is oscillated in one direction, and means for

gripping the shaft immediately upon the turning of the collar in the opposite direction for preventing retrograde movement of said shaft.

2. In a sewing machine, a work support, stitch forming mechanism including a needle, a feeding mechanism including a feed roller located above the work support and in rear of the needle, a freely rotating feed roller mounted beneath the work support and projecting through the opening therein and cooperating with said feed roller above the work support, a shaft mounted in fixed bearings above the work support, a collar mounted on said shaft for free movement thereon, means for oscillating said collar, a spring connected to the collar and wound tightly about said shaft so as to grip the shaft for turning the same when the collar is oscillated in one direction, a second collar mounted on said shaft and held in a fixed position, and a spring attached to said second collar and wound tightly about said shaft so as to grip said shaft to prevent the retrograde movement of the shaft.

3. In a sewing machine, a work support, stitch forming mechanism including a needle, a holding foot yieldingly and continuously pressing on the material and having an opening therethrough for the needle, and a feeding mechanism including a feed roller located above the work support and in rear of the holding foot, a presser bar mounted for vertical movement, and means carried by the presser bar in which said feed roller is mounted for rotation about a horizontal axis fixed relative to the presser bar, means for yieldingly depressing said bar, a shaft mounted in fixed bearings above the work support, a flexible means connecting the shaft to the feed roller whereby it is rotated and permitted to move vertically, a collar on said shaft, means for oscillating the collar, a spring attached to the collar and tightly wound about said shaft whereby when said collar is oscillated in one direction the spring will grip the shaft and turn the same, and when oscillated in the opposite direction it will be freed from the shaft, and means for gripping said shaft immediately upon the spring releasing the same for preventing retrograde movement of the shaft.

4. In a sewing machine, a work support, stitch forming mechanism including a needle, a holding foot yieldingly and continuously pressing on the material and having an opening therethrough for the needle, a feeding mechanism including a feed roller located above the work support and in rear of the holding foot, means for supporting a presser bar on which said feed roller is mounted, means for yieldingly depressing said bar, a shaft mounted in fixed bearings above the work support, a flexible means connecting the shaft to the feed roller whereby it is rotated and permitted to move vertically, a collar on said shaft, means for oscillating the collar, a spring attached to the collar and tightly wound about said shaft whereby when said collar is oscillated in one direction the spring will grip the shaft and turn the same, and when oscillated in the opposite direction it will be freed from the shaft, a second collar freely mounted on said shaft and fixed against movement, and a spring attached to said second collar and tightly wound about said shaft so

as to grip the shaft and prevent retrograde movement thereof.

5. In a sewing machine, a work support, stitch forming mechanism including a needle, a holding foot yieldingly and continuously pressing on the material and having an opening there-through for the needle, a feeding mechanism including a feed roller located above the work support and in rear of the holding foot, means 10 for supporting a presser bar on which said feed roller is mounted, means for yieldingly depressing said bar, a yoke bracket fixed to the machine, a shaft mounted in said bracket, a collar freely mounted on said shaft and attached to one arm 15 of the yoke bracket, a collar freely mounted on said shaft adjacent the other arm of the yoke bracket, means for oscillating said last-named collar, a spring secured to the last-named collar and tightly wound about said shaft so as to grip the shaft to turn the same when the collar 20 is oscillated in one direction and to release the shaft when the collar is turned in the other direction, a second spring attached to the collar fixed to the yoke bracket and tightly wound about said shaft for gripping the same to prevent retrograde movement, and a collar attached to the shaft and located between the springs for separating the same.
6. A feeding mechanism for sewing machines including a feed roller, a shaft connected to said feed roller, a collar freely mounted on said

shaft, means for oscillating the collar, a spring attached to the collar and tightly wound about said shaft for gripping said shaft to move the same when the collar is oscillated in one direction and for releasing the shaft when the collar is oscillated in the other direction, a second collar freely mounted on said shaft and fixed against movement, and a spring attached to said last-named collar and tightly wound about said shaft for gripping the same and preventing retrograde movement therein.

7. A feeding mechanism for sewing machines including a feed roller, a shaft connected to said feed roller, a collar freely mounted on said shaft, means for oscillating the collar, a spring attached to the collar and tightly wound about said shaft for gripping said shaft to move the same when the collar is oscillated in one direction and for releasing the shaft when the collar is oscillated in the other direction, a second collar freely mounted on said shaft and fixed against movement, a spring attached to said last-named collar and tightly wound about said shaft for gripping the same and preventing retrograde movement therein, and a third collar fixed to the shaft and disposed between said springs for preventing endwise movement of the shaft.
